TOOL

William A. Bangel, Redondo Beach, Calif.

Application May 12, 1933, Serial No. 670,651

3 Claims. (Cl. 81—43)

This invention relates to a tool for use in handling small parts of delicate machinery.

In general the device comprises two fingers which are pivotally connected to a body member and which are adapted to swing toward and away from each other for grasping or releasing a part to be handled. A rod, slideable in the body member, with links connecting said rod and the finger members, serves to effect a relative movement of said fingers. In the form of the invention hereinafter described in detail, the fingers are urged apart by pressing downwardly on the rod and are automatically forced together by the aid of a spring device. Recesses may be provided in the lowermost ends of the fingers for accommodating the part to be handled and the shape of said ends and said recesses may be varied to accommodate any particular part, without departing from the spirit of the invention.

Much difficulty is encountered in removing, particularly the second-hand of a watch without breaking the same. It is also difficult to subsequently hold and ream the opening in the hub portion thereof. Applicant has therefore chosen to form the ends of the finger members and the recesses therein to accommodate the second-hand of a watch.

An object of the invention is the provision of a tool which serves as a vise in removing handling or fitting watch-hands or other delicate parts.

Another object is the provision of a tool for removing, handling or fitting delicate parts, which includes two pivotally supported grasping fingers adapted for movement toward and away from each other for grasping or releasing a part and spring actuating means for normally urging said fingers together.

A further object of the invention is the provision of a tool for removing, handling or fitting the second-hand of a watch, which includes two pivotally supported grasping fingers adapted for relative swinging movement and having means formed at their free ends which are cooperative to receive the hub of a second-hand and permit the sleeve portion thereof to project outwardly between said fingers.

Another object is to provide a device of the character above referred to, wherein the grasping fingers are provided with elongated grooves which are cooperative when the fingers are together to define an opening to accommodate a drill or the like when it is desired to ream the hub opening in a second-hand or other delicate part.

A still further object is to provide a tool of the character referred to, which is compact and has a minimum number of working parts, substantially all of which are hidden from view.

This invention possesses many other advantages and has other objects which may be made

more easily apparent from a consideration of one embodiment thereof. For this purpose one form is shown in the accompanying drawing and forming part of the present specification. I shall now proceed to describe this form in detail, which illustrates the general principles of the invention; but it is to be understood that this description is not to be taken in a limiting sense, since the scope of the invention is best defined in the appended claims.

Referring to the drawing:

Figure 1 is an elevation, partly in section, of a tool constructed in accordance with the present invention.

Figure 2 is a vertical sectional view through the tool.

Figure 3 is an end elevation taken as indicated by line 3—3 of Figure 1 and showing the grasping fingers in an open position.

Figure 4 is a transverse sectional view taken as indicated by line 4—4 of Figure 2 and

Figure 5 is an enlarged fragmentary sectional view of the grasping ends of the finger members and showing a second-hand of a watch held therebetween.

Referring more in particular to the accompanying drawing, applicant's invention includes a body portion 10, the outer surface of which may be formed such as to make the tool most easily handled when working with delicate parts. Two depending fingers 11 and 12 are pivotally connected at the lower end of the body member 10 as by the aid of pivot pins 13 and 14. Said fingers are adapted to be moved toward and away from each other in a manner more fully hereinafter set forth, for the purpose of grasping or releasing a part to be handled.

In order to make a more compact and neater appearing tool, applicant prefers in the present instance to enclose the pivoted ends of the finger members 11 and 12. He accomplishes this by forming a hollow shell portion 15, (shown in Figures 2 and 4) at the lower end of the body member 10 and into which the somewhat reduced end portions 16 and 17 of the fingers enter. The pivot pins 13 and 14 pass through the reduced portions of the fingers and are supported in the walls of the hollow shell portion 15, as shown clearest in Figure 4. Although not shown, applicant prefers to provide a relatively loose fit between the pivot pins 13 and 14 and the openings in the reduced portions of the fingers. This is for the purpose of further enhancing a free movement of said fingers.

Where exceptionally small and delicate parts are involved, it is desirous to use a very small tool. Applicant is able to construct such a tool in accordance with his invention by arranging the parts in the manner hereinafter described. A tubular guide member 18 is secured in the body

member 10 and projects somewhat below the lower end thereof. The finger members 11 and 12 are provided with semi-circular grooves 19 and 20 which are cooperative when the fingers 5 are closed to define an opening for receiving the lower end of said tube 18. In other words, when the fingers are together, they completely surround said tube as shown in Figure 4. The reduced portions 16 and 17 of the finger members and 10 also the grooves, are curved as at 21 and 22 to permit the fingers to swing on the pivots 13 and 14.

The finger actuating means consists of a rod 23 slidably supported in the guide sleeve 18. It projects below the bottom of said sleeve and carries on its lowermost end an enlarged portion 24. Links 25 and 26 serve to connect said enlarged portion with the finger members 11 and 12. One end of said link members enters slots in the enlarged portion 24 as shown in Figure 3 and is pivotally held therein by a pin 27. The other end of said links 25 and 26 enter recesses 28 and 29 in the fingers 11 and 12 respectively and are pivotally held therein by the aid of pivot pins 30 and 31.

25 The rod 23 may be urged downwardly to spread the fingers apart, as by the aid of a button 32 at its upper end. Said button has an extended portion 33 which enters a spring receiving chamber 34 in the upper end of the body member 10 and 30 is screw threaded onto said rod. A coiled spring 35 between a shoulder 35a on said extended portion 33 and a shoulder 36 at the bottom of said chamber, serves to urge the rod upwardly for normally holding the fingers together.

35 As heretofore stated, the shape of the free ends of the finger members and also the recesses formed therein, may be varied without departing from the spirit of the invention.

In the present instance the grasping ends of 40 said fingers are designed to accommodate a second-hand of a watch as clearly shown in Figure 5. Suitable recesses 36 and 37 are cooperative when the fingers are together for receiving the hub portion 38 of the second-hand, while the 45 usual sleeve 39 is permitted to extend downwardly through an opening 40 defined by the two fingers. In the event that it is desired to enlarge the opening 41 of the sleeve 39, or remove something therefrom, applicant has provided semi-circular grooves 42 and 43 in the finger members, 50 which are cooperative when said members are together to form an opening into which a drill or other tool may enter.

55 From the foregoing description, the actuation of the tool should be clear. When used to remove the second-hand of a watch, the fingers may be moved apart by pressing the button 32 as shown in Figure 1. After placing the fingers on the watch dial and on either side of the second-hand, 60 the button may be released, whereby the spring urges the fingers together and the somewhat sharpened portions 44 of the finger ends serve to pry the second hand loose and urge it into the receiving apertures where it is held as between 65 the jaws of a vise.

I claim:

1. In a device of the character described, in combination a body member having a finger receiving recess in its lower end, coacting gripping fingers extending longitudinally therefrom for relative swinging movement, with their upper ends extending into said finger receiving recess and pivotally connected to the body member 70 within said recess whereby the finger ends are

completely enclosed, said fingers having cooperating part-receiving recesses in their free ends and longitudinally disposed grooves in their adjacent faces communicating therewith and which are cooperative when the gripping fingers are together for receiving a tool or the like, an operating rod slidable in the body member and extending between the gripping fingers for positively swinging the same to and from each other, links connecting the lower end of said rod with said gripping fingers, one end of said links extending into recesses formed in the adjacent faces of the gripping fingers and pivotally held therein, said fingers having further longitudinally disposed grooves in their adjacent faces which are cooperative when said fingers are together for receiving that portion of the operating rod extending therebetween and permitting the engagement of their adjacent faces along their length whereby to completely enclose said operating rod and links, and a coil spring in the upper end of the body member which acts on said rod for normally holding the gripping fingers together.

2. In a device of the character described, in combination, a body member having a spring receiving recess in its upper end and a finger receiving recess in its lower end, coacting gripping fingers depending from the lower end of said body member for relative swinging movement toward and from each other, with their upper ends extending into said finger receiving recess and pivotally connected to the body member within said recess whereby said finger ends are completely enclosed, an operating rod slidable longitudinally in the body member and extending therebelow into a longitudinal opening defined by cooperating grooves in the adjacent faces of the gripping fingers, links connecting the lower end of said rod with said gripping fingers, one end of said links extending into slots formed in the adjacent faces of the fingers and pivotally held therein, said fingers having flat adjacent faces which are adapted to normally meet along their length whereby to completely enclose said links and operating rod, and a coil spring in the spring receiving recess which acts on said rod for normally holding the gripping fingers together.

3. In a device of the character described, in combination, a body member having a spring receiving recess in its upper end and a finger receiving recess in its lower end, coacting gripping fingers depending from the lower end of said body member for relative swinging movement toward and from each other, with their upper ends extending into said finger receiving recess and pivotally connected to the body member within said recess whereby said finger ends are completely enclosed, a guide member secured to the body member and extending therebelow into a longitudinal opening defined by cooperating grooves in the adjacent faces of the gripping fingers, an operating rod slidable in said guide member and extending therebelow into said opening, links connecting the lower end of said rod with said gripping fingers, one end of said links extending into slots formed in the adjacent faces of the fingers and pivotally held therein, said fingers having flat adjacent faces which are adapted to normally meet along their length whereby to completely enclose the finger operating parts, and a coil spring in the spring receiving recess which acts on said rod for normally holding the gripping fingers together.
